UNITED STATES PATENT OFFICE.

JOHN G. CARLINET, OF PHILADELPHIA, PENNSYLVANIA.

PNEUMATIC TOOL.

SPECIFICATION forming part of Letters Patent No. 574,784, dated January 5, 1897.

Application filed May 19, 1896. Serial No. 592,208. (No model.)

To all whom it may concern:

Be it known that I, JOHN G. CARLINET, a citizen of the United States, residing at Philadelphia, in the county of Philadelphia and State 5 of Pennsylvania, have invented certain new and useful Improvements in Pneumatic Tools; and I do hereby declare the following to be a full, clear, and exact description of the invention, such as will enable others skilled in the 10 art to which it appertains to make and use the same.

This invention relates to improvements in pneumatic tools for cutting stone, metal, and other substances, and has for its object the 15 providing of a tool adapted to be operated by air or other fluid pressure in such a manner as to deliver a sharp quick blow to the chisel or cutting-tool while imparting the least possible vibration to the hand of the operator.

20 This invention consists of the novel construction and arrangement of parts, as will be hereinafter more fully explained.

Referring to the accompanying drawings, Figure 1 represents a central longitudinal sectional view of the tool, showing the arrangement of the interior portions and also a portion of a chisel or other cutting-tool carried thereby. Fig. 2 represents a cross-sectional view taken along the line 2 2 of Fig. 1. Fig. 30 3 represents a cross-sectional view taken along the line 3 3 of Fig. 1, and Fig. 4 represents a cross-sectional view taken along the line 4 4 of Fig. 1. Fig. 5 represents a central longitudinal sectional view showing the arrangement of the interior portions after the tool has been acted on by a charge of air or fluid, and Fig. 6 represents a form of handle 35 adapted to be used in connection with the herein-described pneumatic tool to stop the 40 operation of the latter at any desired time.

Similar parts are represented by similar letters throughout the several views.

The tool is provided with a casing A, one end of which engages the tubular screw B, 45 and the rear end of the casing is closed by means of the plug or closing-screw D. The casing A is provided with a recess a, and its cross-section is thickened, as at a', forming an inner flange. The tubular screw B is provided with a chamber C and an exhaust-port b, or, instead of having the port b, a port b' may

be drilled through the front of the screw, in which case the exhaust through port b' would act as a blast to remove the chips and dust. The closing-screw D is provided with the 55 ports d, d', and d².

M represents an anvil held partly by the thickened portion a' of the casing and partly within the chamber C.

L represents a portion of a chisel or other 60 cutting-tool passing through one end of the closing-screw D and held by the anvil M.

N represents a spiral spring within the chamber C and exerting a pressure on the face of the anvil M and on the face of the 65 tubular screw B, and consequently on the casing, so as to normally hold the parts in the position shown in Fig. 1. The anvil M is provided with the socket m and ports m' and m².

H represents a central inlet-pipe, one end of which is made solid and shaped to fit the socket m of the anvil and slightly flattened at that end, as at h³. The said pipe is screw-threaded, as at h⁰, to receive a hose-coupling. 70 This inlet-pipe H is provided with a central passage or duct h and the ports h' and h².

The top and bottom of the pipe H is flattened, as at h³, where it passes through the rear end closing-screw D, the object of which is to afford 80 an exhaust-passage from the chamber F. In order to prevent the pipe H from sliding entirely out of the tool, a pin P is inserted, which, engaging the flattened portion of the pipe, will only allow a movement of the pipe equal 85 in extent only to the length of the flattened portion thereof.

E represents a plunger or striker adapted to fit snugly within the casing A and to move back and forth under pressure in such a manner as to strike the anvil M and operate the chisel. This plunger M is provided with a central aperture, in which slides the pipe H, or the plunger may be said to slide on the pipe H. In the rear end of the said plunger 90 is a cavity e³, and near the other end are the ports e, e', and e². The space within the casing between the rear end closing-screw and the plunger forms a chamber F, while the space between the other end of the plunger 95 and the anvil and projection a' forms a second chamber K, into both of which chambers

the air or other fluid under pressure passes and imparts the requisite motion to the moving parts.

The operator having placed the point or 5 blade of the chisel against the surface to be cut, he holds the chisel with one hand while he presses the pipe H with the other until he feels it come in contact with the anvil. When so held, the parts of the tool may be said to be 10 in their initial positions for action, and the operation of the tool from this point is as follows:

Referring to Fig. 1, which represents the parts in their initial positions, it will be seen that the parts are so arranged that the chamber F is in direct communication with the 15 passage h, and the chamber K is open to exhaust through the ports m^1 , chamber C, and port b. In this position the air or other fluid under pressure enters the chamber F from the central duct h through the ports h' , d , and d' . The plunger E, then being the portion which presents the least resistance to the air or other fluid, will be driven quickly forward, striking a sharp blow on the anvil M. The plunger E, 20 after striking the anvil, stops against the same, and the air in chamber F, reacting on the face of the closing-screw D, will force the whole casing backward, compressing the spring N until the parts assume the position shown in Fig. 5. In this position the chamber F is now 25 open to exhaust through the ports d' , d , d^3 , and d^4 , and the chamber K is open to the air or other fluid supply from duct h through ports h^2 , e , e' , and e^2 , while the exhaust to that 30 chamber is closed. When the parts assume the above position, the air or other fluid under pressure entering the chamber K forces the plunger back, and the casing and other parts assume their initial positions. The motive 35 fluid may now be again admitted and the operation repeated. It will be seen that when the plunger E moves forward under pressure of the air or other fluid in the chamber F the port e comes in front of the port h^2 , but it 40 will be observed that the admission of air or other fluid into the chamber K will not take place until the port e^2 comes in front of the recess a' through the backward motion of the casing, as above described. 45 Instead of exhausting the air or fluid from chamber F through ports d , d' , d^3 , and d^4 a port e^4 may be drilled through the casing, so that when the parts assume the position shown in Fig. 5 the exhaust will take place through 50 ports h^3 , d^3 , &c., in supply-pipe H.

The small passage m^1 , communicating with the socket m and port m^2 , acts to relieve any pressure that might be caused in front of the 55 pipe H through leakage of the socket-joint. In some cases, especially where large tools are used, it is advisable to employ some additional means for arresting the motion of the tool when once started. I accomplish this by 60 the arrangement shown in Fig. 6, which constitutes a sliding handle. When such a han-

dle is employed, the central pipe H is modified, as represented by H'. The duct h is partitioned, as at h^9 , and two ports h^7 and h^8 , drilled through the pipe H, communicate with the central duct, one on each side of the partition h^9 .

T represents a piece of hose, and V a hose-coupling screwed to the end of the pipe H. The sliding handle consists of the casing A', provided at one end with the closing-screw D'. An inner sleeve R is carried within the casing, and the space between the said sleeve and the pipe H, which it surrounds, forms the chamber S.

The packing Q is provided to prevent leakage through the ends. It will be seen that in order for the air or other fluid to reach the tool proper, or the duct on the right of the partition h^9 , it will have to pass from the duct 85 on the right through the port h^7 , chamber S, and port h^8 . The above can take place when the sliding handle occupies the position shown in the figure, but suppose the handle to be moved backward, or to the left, then the port 90 h^8 would be closed and the admission of air or other fluid to the tool will be cut off.

When the front face of the casing A' is in contact with the shoulder h^9 , then the positions of the parts will be such as to admit the 95 air or other fluid into the tool, but when the handle is carried to the left, so that the plug D' strikes the portion v of the hose-coupling, the air or other fluid will be cut off and the tool will stop its operation.

It will be seen from the above that a tool is provided in which a maximum velocity is imparted to the chisel or cutting-tool with a minimum amount of motion of the casing. This insures a heavy blow by the cutting-tool 105 with small vibration of the hand of the operator.

It will be further observed that the parts are extremely simple and that the tool may be easily taken to pieces and cleaned, but it is 110 obvious that although I have shown only one form of tool the same is capable of modification in proportion and minor changes in construction without departing from the spirit of my invention.

What I claim, and desire to secure by Letters Patent of the United States, is—

1. In a pneumatic tool, the combination, with a casing closed at both ends, of a plunger adapted to move within the said casing, an anvil adapted to be struck by the forward motion of said plunger, a cutting-tool carried by said anvil, and means for admitting and exhausting fluid under pressure at the ends of the said plunger through an alternate motion of the casing, substantially as described.

2. In a pneumatic tool, the combination, with a casing provided with closing-screws at each end, of a plunger adapted to move within the said casing, an anvil also within said casing and adapted to be struck by the forward motion of the said plunger, a central supply-

pipe and means for alternately admitting and exhausting the motive fluid at the ends of the aforesaid plunger, substantially as described.

3. In a pneumatic tool, the combination,

- 5 with a casing provided with front and rear closing-screws having admission and exhaust ports, of a plunger provided with ports and adapted to move within the said casing, an anvil also provided with ports and carried by
- 10 the aforesaid casing and front closing-screw, a cutting-tool carried by the said anvil and passing through said front closing-screw, and a central supply-pipe provided with ports, and passing through the rear end closing-
- 15 screw, and the plunger, and engaging the said anvil, substantially as described.

4. In a pneumatic tool, the combination with a casing provided with front and rear end closing-screws having admission and ex-

- 20 haust ports, of a plunger provided with ports and adapted to move within the said casing, an anvil provided with ports and carried by the said casing and the front end closing-screw, a cutting-tool carried by the said an-
- 25 vil and passing through the said front closing-screw, and a central supply-pipe having a solid head, provided with ports and passing through the aforesaid rear end closing-screw and plunger, substantially as described.

- 30 5. In a pneumatic tool, the combination with a casing provided with front and rear end closing-screws having admission and exhaust ports, of a plunger carried within the said casing, an anvil provided with ports, car-

- 35 ried within the said casing and front closing-screw and adapted to be struck by the forward motion of the plunger, a cutting-tool carried by the said anvil and passing through the said front closing-screw, a central sup-
- 40 ply-pipe, made solid at one end, provided with ports and passing through the said rear closing-screw and plunger and adapted to engage said anvil, substantially as described.

- 45 6. In a pneumatic tool, the combination, with a casing provided with a rear end closing-screw having admission and exhaust ports, of a second closing-screw inserted in the other end of the said casing and provided with exhaust-ports and a central chamber; a

- 50 plunger provided with ports and adapted to move within said casing; an anvil provided with ports and carried by said casing and front closing-screw; a cutting-tool carried by the said anvil, a central supply-pipe made solid at one end, provided with ports and pass-
- 55 ing through the said rear closing-screw and plunger, and engaging the anvil, substantially as described.

- 60 7. In a pneumatic tool, the combination, with a casing, of a closing-screw provided with a central chamber and exhaust-port and inserted in one end of the casing, a rear closing-screw provided with ports and inserted in the other end of the said casing, a plunger pro-
- 65 vided with ports and adapted to move within the said casing, an anvil provided with ports and carried within said casing and front clos-

ing-screw, a cutting-tool carried by the said anvil, means for resisting the forward motion of the said anvil carried by the said front clos- 70 ing-screw, and a central supply-pipe, provided with ports and adapted to be engaged by the rear end closing-screw plunger and anvil, substantially as described.

8. In a pneumatic tool, the combination,

- 75 with a casing provided at each end with a closing-screw having admission and exhaust ports, of a plunger adapted to move within said casing, an anvil carried within said casing and front closing-screw and adapted to be struck by said plunger, a cutting-tool carried by said anvil, a spring adapted to resist the forward motion of the said anvil, and means for admitting and exhausting fluid alter-
- 80 natively to and from both ends of the said 85 plunger, substantially as described.

9. In a pneumatic tool, the combination with a casing provided with closing-screws at each end having admission and exhaust ports, of a plunger provided with ports and adapted 90 to move within the said casing; an anvil carried within the said casing and provided with ports and front and rear cavities or sockets, a cutting-tool carried by said anvil in the front socket, a spring adapted to resist the 95 forward motion of the said anvil, and a central supply-pipe provided with ports, passing through the said rear closing-screw and plunger and adapted to engage the rear socket of the aforesaid anvil, substantially as de- 100 scribed.

10. In a pneumatic tool, the combination with a casing of a closing-screw having ports and provided with a central chamber, of a second closing-screw provided with ports and 105 inserted in the other end of said casing, a plunger and ports therein carried within said casing, an anvil also provided with ports and carried within the said casing and clos- 110 ing-screw chamber, a cutting-tool carried by 110 said anvil, a spring carried within said clos- 115 ing-screw chamber and adapted to resist the forward motion of said anvil, a central inlet-pipe having a solid head, provided with ports and passing through said rear end closing- 115 screw and plunger and adapted to engage the aforesaid anvil, substantially as described.

11. In a pneumatic tool, the combination with a casing, of a closing-screw provided with a central chamber and ports and inserted 120 in one end of said casing, a second closing-screw provided with ports and inserted in the other end of said casing; a plunger provided with ports and carried within the said casing; an anvil also provided with ports and carried 125 within the said casing and closing-screw cham- 125 ber, a cutting-tool carried by one end of said anvil; a spring carried within said closing- 130 screw chamber and adapted to resist the for- 130 ward motion of said anvil and carried by said closing-screw chamber; a central supply-pipe having a solid head at one end and adapted to be connected to the source of fluid-supply at the other provided with ports and passing

through the rear closing-screw and plunger and adapted to engage said anvil, substantially as described.

12. In a pneumatic tool, the combination with a casing, of a closing-screw provided with a central chamber and inserted in one end of said casing, a second closing-screw inserted in the other end of said casing, a plunger adapted to move within said casing, an anvil adapted to be struck by said plunger and carried within said casing and closing-screw chamber, a cutting-tool carried by said anvil, a central supply-pipe having a solid head at one end and adapted to be connected with the source of fluid-supply at the other, provided with ports and passing through the rear closing-screw and plunger and adapted to engage the said anvil, and ports provided for the admission and expulsion of the fluid at the ends of the said plunger, substantially as described.

13. In a pneumatic tool, the combination, with a casing provided with closing-screws in each end having admission and exhaust ports; of a plunger provided with ports and carried within the said casing, an anvil carried within the said casing and front closing-

screw and provided with ports, a cutting-tool carried by the said anvil, a spring carried within the front closing-screw and adapted to resist the forward motion of the said anvil, a central supply-pipe, having a solid head at one end and adapted to be connected with the source of fluid-supply at the other end, passing through the rear end closing-screw and plunger and engaging the said anvil, means for limiting the motion of the said supply-pipe, substantially as described.

14. In a pneumatic tool, the combination with a sliding casing closed at both ends and adapted to act as a valve, of a plunger carried within the said casing, an anvil adapted to be struck by the forward motion of said plunger, a cutting-tool carried by the said anvil, and means for admitting and exhausting fluid at the ends of said plunger through the alternate motion of the said casing, substantially as described.

In testimony whereof I affix my signature in presence of two witnesses.

JOHN G. CARLINET.
